CLAIM

The ornamental design for an adhesive liner for a wearable drug delivery device, as shown and described.

DESCRIPTION

FIG. 1 is a top perspective view of an adhesive liner for a wearable drug delivery device;

FIG. 2 is a bottom perspective view of the adhesive liner of FIG. 1;

FIG. 3 is a top plan view of the adhesive liner of FIG. 1; FIG. 4 is a left side elevational view of the adhesive liner of FIG. 1;

FIG. 5 is a right side elevational view of the adhesive liner of FIG. 1;

FIG. 6 is a front elevational view of the adhesive liner of FIG. 1;

FIG. 7 is a back elevational view of the adhesive liner of FIG. 1; and,

FIG. 8 is a bottom plan view of the adhesive liner of FIG. 1.

The broken line showing of parts of the drawings is included for the purpose of illustrating use and environment and forms no part of the claimed design.
